Primary Examiner — Rosemary K Tarcza*(74) Attorney, Agent, or Firm* — Morgan, Lewis & Bockius LLP(57) **CLAIM**

The ornamental design for a wireless charging device, substantially as shown and described.

DESCRIPTION

FIG. 1 is a perspective view of a wireless charging device showing our new design.

FIG. 2 is a front view of the wireless charging device.

FIG. 3 is a back view of the wireless charging device.

FIG. 4 is a right-side view of the wireless charging device.

FIG. 5 is a left-side view of the wireless charging device.

FIG. 6 is a top view of the wireless charging device; and,

FIG. 7 is a bottom view of the wireless charging device. The broken lines are included for purposes of illustrating portions of the wireless charging device that form no part of the claimed design.
